H. S. MYERS.

HOIST BRAKE.

APPLICATION FILED FEB. 27, 1922.

1,413,421.

Patented Apr. 18, 1922.

Harry S. Myers Inventor
By John D. Shoemaker Attorney

UNITED STATES PATENT OFFICE.

HARRY S. MYERS, OF VAN, PENNSYLVANIA.

HOIST BRAKE.

1,413,421.

Specification of Letters Patent. Patented Apr. 18, 1922.

Application filed February 27, 1922. Serial No. 539,583.

To all whom it may concern:

Be it known that I, HARRY S. MYERS, a citizen of the United States, residing at Van, in the county of Venango and State of Pennsylvania, have invented certain new and useful Improvements in Hoist Brakes, of which the following is a specification:

This invention relates to a hoisting brake, and more particularly to such a brake comprising a band and track associated with a winding drum and means for causing the band to bind or grip the track.

The invention may be embodied in any type of machinery wherein a brake of large power is desirable, but I have selected for the purpose of illustration its use in a hoist attachment for tractors in which a drum supporting frame is mounted upon the differential housing of a Fordson tractor.

The object of the invention is to provide a brake of the type, which is powerful in operation, easily operated and within convenient reach of an operative of hoist machinery. A further object is the provision of operating means for such a brake which occupies a minimum of space, and operates with a minimum of friction. A still further object of the invention is the efficient mounting and spacing of an eccentric upon a shaft so that the parts will not bind upon each other in operation. Other objects and advantages of the invention will hereinafter appear in the following description and the novel features thereof will be particularly pointed out in the appended claims.

Like reference numerals indicate like parts throughout the several figures of the drawings, in which—

Figure 1 is a sectional view through a hoist attachment for a tractor showing the parts of my improved brake and operating means in side elevation,

Figure 2 is a rear elevation of one corner of said hosting attachment showing my improved brake operating means,

Figure 3 is a sectional view of the operating means taken upon the line 3—3 of Figure 1, and

Figure 4 is a view of a modified form of shaft and lever in one piece.

It will be understood that the principles of my invention may be embodied in various forms and that the special embodiment thereon shown and described in this instru-

ment is merely indicative of those principles. It has, however, been found to be a practical and efficient embodiment and one which in use has produced excellent results in the special hoisting mechanism in connection with which it has been used.

In order that my invention may be clearly understood it is necessary to briefly outline the particular hoisting attachment in which it has been shown as used before proceeding with a detail description of the parts comprising the brake mechanism. A full and complete description of this hoisting attachment is given in my copending applications for patents identified as follows: Serial Number 518,980, filed November 30, 1921, for hoist attachment for tractors; Serial Number 532,992, filed January 31, 1922, for winding drums, and Serial Number 533,956, filed February 3, 1922, for arrangement of winch elements.

The frame of the hoist attachment comprises vertical supporting members 10 adapted to be attached to the differential housing of a tractor, shown in outline in Figure 1, horizontal rails 11 and 12, to which are attached bearing carrying elements 13 suitably braced as shown partly in dotted lines in Figure 1. The elements 13 have horizontally disposed portions supporting bearings 14, in which is mounted a drive shaft 15, and vertically disposed portions supporting bearings 16, in which is mounted a drum shaft 17. The drum of the hoist is indicated by the numeral 18, and has associated with it a brake track 19 on which the band 20 rests and is held between the flanges 21 and 22.

Rising from the bearings 14 of the drive shaft are apertured ears or bearings lugs 23 and 24, in which is mounted a brake operating shaft 25 projecting beyond the ears or lugs 23 and 24. Upon one end of the shaft is mounted the eccentric 26 keyed to the shaft 25 by a key 27, it being understood that the shaft is provided with a groove of a length to neatly receive the key while the eccentric is grooved for its entire width.

Upon the shaft and at either side of the eccentric are one or more washers 28 and 28' which have a diameter sufficient to project beyond the eccentric surface to form retaining means for the band 20. It will be noted that these washers will maintain the

eccentric upon the key and prevent undue lateral movement of the eccentric upon the shaft. The key has been shown in Figure 3 as slightly longer than the width of the eccentric which will ordinarily maintain the washers slightly spaced from the eccentric, especially when the eccentric has a driven fit with the key. Upon the opposite end of the shaft 25 is mounted in any suitable manner the lever 29. While I have shown the means for attaching the hub 30 of the lever to the shaft as a set screw 31, it will be appreciated that the means so employed might take any form and embody if desirable a non-circular shaft end and hub aperture.

In Figure 4 I have shown a modified form of shaft and lever in one piece, which has been found to be satisfactory in use. The two parts are made of round stock and bent at a sharp angle at a suitable point to provide the upstanding lever.

It will be appreciated that the washer 28 and pin 32 will prevent the movement of the eccentric upon the shaft in one direction and that the washer 28' abutting the ear 23 will act as a stop for the eccentric in the opposite direction. The shaft is also prevented from undue movement laterally in the ears 23 and 24 by these parts. As the washers may either rotate with the shaft or rotate thereon, the friction is reduced to a minimum. For instance, when the washer 28' abuts the ear 23, the band 20 under the influence of the flange 22 will lie against the washer 28, which is free to rotate with the shaft and eccentric. The only friction then would be between the end of the key 27 and the washer 28'. When the hub 30 abuts the ear 24, the washers are free to rotate with the shaft and the only friction will be between the hub and ear.

The band 20 is passed around the eccentric and the loop is completed in any desired manner, as by welding. I have shown a rivet or bolt 32' passing through the end and the body of the band. The opposite end of the band has welded thereto a bolt 33 having its screw threaded end passing through the rail 12 and secured by lock nuts 34.

It will be seen that the lever 29 in its inactive position can be readily reached and operated from a point to the rear of the tractor or from the seat thereof. The usual point of operation of the brake is at the rear of the tractor, when the lever is thrown in the direction of the arrow in Figure 1. In the applying of the brake, the eccentric will not only tighten the band upon the track, but will cause slightly more of it to come into contact with the track.

From the foregoing description the operation of the brake will be apparent. It remains only to point out the economy of space

occupied by this particular construction of parts.

In hoist attachments of this type, the available space is that which is defined by the distance between the tractive wheels. All of the hoist elements must be placed within this width of space. It will be noted that the eccentric and washers take only the width occupied by the brake track and flanges, that the ears occupy the width of the drive shaft bearing, and that the hub 30 occupies only part of the width of the hub 35 of the drive sprocket wheel. My brake is therefore one of a few number of standard parts and occupies a minimum of space.

Having described my invention, what I claim as new and desire to secure by Letters Patent is:

1. In a brake for hoist drums, a brake track, a band adapted to grip said track and having a looped end, a shaft, an eccentric lying in said looped end and adapted to be slid upon the shaft and to rotate therewith, means for limiting the movement of the eccentric upon said shaft and for maintaining said looped end upon said eccentric, and means for operating said shaft and eccentric to cause said band to bind said track.

2. In a brake for hoist drums, a brake track, a band adapted to grip said track and having a looped end, a shaft, an eccentric lying in said looped end and keyed to said shaft, washers held on said shaft in proximity to the ends of the key and extending beyond the surface of said eccentric for maintaining said eccentric upon said shaft and said looped end upon said eccentric, and means for rotating said shaft and eccentric to cause said band to bind said track.

3. In a hoisting machine comprising a frame element carrying drum and brake shaft bearings, a drum shaft supporting a brake track and associated band in close proximity to said frame element, a brake shaft having its end projecting beyond its bearing, an eccentric mounted upon the projecting end of said brake shaft and encircled by the looped end of said band and held in alignment with said brake track, means for rotating said brake shaft and eccentric to cause a binding of the band to the track.

4. In a brake for hoisting drums, a brake track, a band adapted to grip said track and having a looped end, a shaft, an eccentric lying within said looped end and keyed to said shaft, the key being slightly longer than the width of said eccentric and lying in a groove in said shaft of a length to receive the same, washers rotatably mounted upon said shaft at each side of said eccentric, and means for maintaining said washers in substantial abutment with the ends of the key, whereby the eccentric is held upon said shaft.

5. In a hoisting attachment for tractors comprising a framework, bearings upon the frame for drive and driven shafts, a drum and associated brake track and band, a brake operator comprising a shaft mounted in bearing means of a width not in excess of the bearing for said drive shaft, and an ec-

centric and loop retaining means of a width not in excess of said brake track, and means for maintaining said eccentric in alignment 10 with said brake track.

In testimony whereof I affix my signature.

HARRY S. MYERS.
